DUPLICATOR

Kenneth O. Christianson, Mankato, Minn., assignor to Creative Educational Society, Mankato, Minn., a partnership composed of G. R. Peterson, J. C. Mackin, A. D. Tinkler, and K. O. Christianson

Application March 10, 1938, Serial No. 195,080

8 Claims. (Cl. 101—131)

This invention relates to new and useful improvements in duplicators, and an object of the invention is to provide such a device which is exceedingly simple and convenient to operate, and the construction of which is such that each impression will be accurately placed on the sheet.

5 A further object is to provide a duplicator comprising a printing frame provided with means at one end for clampingly securing the sheets to be printed thereto in superimposed relation, and which means also serves to square the printing member or rocker with the sheets supported on the printing frame.

10 A further object is to provide a printing blanket having novel means for detachably securing it to the rocker, whereby it may readily and conveniently be detached therefrom, when necessary, and a new one substituted therefor.

15 Other objects of the invention reside in the novel construction of the printing frame, which has a channel member at one end providing a clamp for detachably securing a stack of sheets to be printed to the printing frame; in the suction means provided on the printing frame for securing it in operative position upon a table or other flat surface; in the novel construction of the hook elements provided at the ends of the blanket for detachably securing it in position on the rocker; and, in the simple and inexpensive construction of the apparatus, whereby it may 20 readily be manufactured and sold to the trade at comparatively low cost.

25 Other objects of the invention will appear from the following description and accompanying drawings and will be pointed out in the annexed claims.

30 In the accompanying drawings there has been disclosed a structure designed to carry out the various objects of the invention, but it is to be understood that the invention is not confined to the exact features shown as various changes may be made within the scope of the claims which follow.

35 In the drawings:

40 Figure 1 is a longitudinal sectional view of my improved duplicator, showing the general construction thereof;

45 Figure 2 is a plan view of the apparatus;

50 Figure 3 is a perspective view showing one end of the rocker with one end of the blanket detached therefrom;

55 Figure 4 is a perspective view of the convexed or curved surface of the rocker, showing the manner of transferring an impression thereon from a master sheet; and

Figure 5 is a longitudinal sectional view showing a rocker of slightly different construction.

The novel duplicator herein disclosed is shown comprising a printing frame, generally indicated by the numeral 2, and comprising a plate 3, preferably having suitable rails 4 and 5 at the ends thereof, as best shown in Figure 1. Two or more suction cups 6 of conventional construction, are secured to the front rail 4 for securing the frame to a table top or other relatively smooth surface. 10 If deemed necessary similar suction cups may be provided at the opposite end of the frame 2.

The sheets to be printed are placed upon the plate 3 of the frame, preferably in the form of a stack, as shown at 7 in Figure 1. Suitable upright alining pins 8 are secured to the frame 2 at one end, against which one edge of the stack of sheets 7 may be engaged to aline or square the pack of sheets with the frame 2.

Means is provided for clamping or securing the pack of sheets to the frame 2, whereby they are not likely to become disarranged on the frame, when impressions are successively made on said sheets. Such means is shown comprising an elongated channel-shaped member, generally indicated by the numeral 9. This member is shown made of sheet metal and has its upper wall curved to provide an outwardly facing concave wall whose upper edge is bent outwardly and downwardly to provide an upright abutment wall 11, 30 as best shown in Figure 1. The lower edge of the wall 11 is adapted to engage the uppermost sheet of the pack 7. Suitable clamping elements, which may be in the form of wing nuts 12, are received in threaded engagement with screws or 35 studs 13 anchored to the front cross rail 4. When the wing nuts 12 are turned in one direction, the lower edge of the upright wall of the clamping member 9 will be forced into engagement with the upper sheet of the pack, thereby firmly securing the pack to the frame in proper relation with respect thereto.

Another important feature of the invention resides in the novel construction of the means for transferring the impression onto each sheet 45 of the pack 7. Such means is shown comprising a rocker, generally indicated by the numeral 14. This rocker has a convex wall 15 against which the usual printing blanket, generally indicated by the numeral 16, is seated. The frame 50 of the rocker 14 comprises side walls 17 and 18 having inwardly turned flanges 19, which are suitably secured to the curved wall 15 to provide in effect, an integral structure. The opposite ends of the curved wall 15 are bent inwardly to 55

provide horizontal flanges 21. These horizontal flanges are suitably secured to the upper flanges 22 of the side walls 17 as, for example, by spot welding.

5 A suitable handle 23 is provided on the rocker 14 and has its ends suitably secured to the flanges 21 by such means as screws 24. The handle extends lengthwise of the rocker, whereby it provides a very convenient grip for an operator, 10 when manipulating the rocker upon the printing frame.

Another feature of the invention resides in the means provided for securing the printing blanket 16 to the curved wall of the rocker. The 15 body of the printing blanket 16 is of more or less standard construction, and embodies a layer of gelatin which may be secured to a suitable inelastic fabric which forms a backing therefor. The printing blanket is, as is well-known, 20 capable of receiving an impression 25 from a master sheet 26, as shown, for example, in Figure 4.

The means for detachably securing the printing blanket to the rocker is best illustrated in 25 Figure 3, and as here shown, comprises a pair of bars 27, one secured to each end of the blanket by suitable means such as small rivets 28. To prevent tearing of the printing blanket 16 at the points where the rivets 28 pass through, suitable 30 bars 30 are fitted against the opposite side of the blanket in alinement with the bars 27. These bars are apertured to receive the rivets 28, whereby the backing sheet of the blanket is securely clamped between the bars 27 and 30. Each bar 27 35 is provided with spaced hook elements 29 which are substantially S-shaped in cross-section. These hooks are adapted to be selectively received in slots 31 or 32 provided in the horizontal flanges 21 of the rocker. Note particularly Figure 1, wherein the blanket is shown in operative 40 position upon the rocker. Because of the unique shapes of the hook elements 29, they are not likely to become disengaged from the slots 31 or 32, when the printing blanket is secured to the 45 rocker.

By reference to Figure 1, it will be noted that the bars 27 to which the hook elements 29 are secured, are spaced inwardly from the edges 33 of the backing of the printing blanket 16. By 50 thus inwardly spacing the hooks 29 from the opposite ends of the blanket, these overhanging ends may readily be grasped by the operator, whereby the operation of removing or mounting the printing blanket upon the rocker is facilitated. By providing two slots 31 and 32 in each 55 horizontal flange 21 of the rocker, the printing blanket may be kept under the proper tension by simply inserting the hooks in the proper slots, as will readily be understood.

60 In the operation of this novel device, the pack of sheets to receive impressions is placed upon the plate 3 of the printing frame 2, with one edge engaging the pins 8. When thus positioned, the lower edge of the upright wall 14 of the 65 clamping member 9 will be positioned upon the uppermost sheet of the stack, whereby when the wing nuts 12 are tightened, the sheets will be firmly clamped in position upon the printing frame in square relation thereto.

70 The rocker is then operated upon the sheets, as shown in Figure 1, it being understood that a printing blanket bearing the desired impression or character, has first been secured to the rocker. In making the impression on each sheet, the 75 forward end of the rocker is conveniently abutted

against the abutment wall 11 of the clamping member 9, as shown in full lines in Figure 1, whereby it is squared with respect to the sheet. It is then rocked backwardly to the position shown in dotted lines in Figure 1, and as it reaches the position shown in dotted lines, it may be lifted upwardly from the printing frame by the operator. When the rocker is thus lifted off the printing frame, the free or bottom end of the sheet which has just received an impression, will 10 be lifted off the pack, because of its tendency to adhere to the printing surface at the point A in Figure 1. Such adherence of the printed sheet to the rocker enables the operator to readily grasp the free end of the printed sheet and swing 15 it upwardly to the dotted line position shown at B in Figure 1, after which it may drop by gravity to the dotted line position indicated at C. It will thus be seen that, if desired, the entire pack of sheets may be printed without removing any of 20 the sheets from the frame 2.

The apparatus has been found very practical and convenient to operate, and may be operated by an inexperienced person with perfect results.

In Figure 5, there is shown a rocker 34 of 25 slightly different construction, whose body is preferably formed of a molded material for example, such as Bakelite. The rocker 34 has a suitable handle 35 whereby it may be conveniently operated. 30

In the form shown in Figure 5, an inwardly turned flange 36 is secured to one end of the rocker adapted to be engaged by a hook element 37, secured to one end of the printing blanket 38. The main body of this blanket is constructed 35 in a manner similar to the blanket 16 shown in the previous figures.

A transverse groove or recess 39 is provided in the upper surface of the opposite end of the rocker 34 adapted to receive a clamping member 41, preferably in the form of an inverted channel, as shown. This channel member is shown provided at each end with an arm 42 mounted on suitable pivot pins or a shaft 43, whereby the clamping member 41 may be swung upwardly to 45 an inoperative position, as shown in dotted lines in Figure 5. The arms 42 also inseparably connect the clamping member 41 to the rocker. A keeper 44 is pivotally supported upon a pivot screw 45, whereby it may be swung to a position 50 over the channel member 41 to secure it in locked position, as shown in full lines in Figure 5. When the keeper 44 is turned at substantially right angles to the position shown in Figure 5, the channel member may be swung upwardly to inoperative position, whereby the printing blanket 38 may readily be detached from the rocker.

To attach the printing blanket to the rocker 34, the end thereof having the hook 37 is attached to the inclined flange 36. The blanket is 60 then pulled tautly around the convexed or rounded surface of the body of the rocker and has its opposite end pulled inwardly over the groove 39 provided in the upper surface of the opposite end of the rocker. The channel member 41 is then swung downwardly into engagement with the end of the blanket and the keeper swung into locking position over the channel member 41, as shown. The free end portion of the blanket is preferably bent backwardly upon 65 itself, before the clamping member is securely locked in the groove 39. The rocker shown in Figure 5 is operated in identically the same manner as the one shown in Figures 1 and 3.

A feature of the present invention resides in the 75

unique construction of the printing blanket, whereby it may readily be removed from the rocker and a new one substituted therefor, when necessary. The blanket is inexpensive in construction, and each is supplied with hook elements 29, as shown in the drawings. Thus, a supply of these blankets may be carried in stock to facilitate making different impressions which, as previously stated, is a very desirable feature.

10 I claim as my invention:

1. In a duplicator, a printing frame upon which the sheet to be printed is supported, means at one end of the frame for squaring the sheet thereon, and a clamping member engageable with said end of the sheet and adapted to securely clamp the sheet in position on the frame, whereby the sheet cannot be displaced on the frame by a printing member, when the latter is operated to make an impression on the sheet, said 15 clamping member having an upright wall adapted to be engaged by one end of the printing member, thereby to square said member with the sheet.

2. In a duplicator, a printing frame adapted to receive a stack of sheets to be printed, spaced pins at one end of said frame engageable with one edge of said stack of sheets, thereby to square the stack upon the frame, an elongated clamping member comprising a flange having its lower 20 edge adapted to engage the adjacent upper surface of the pack of sheets, means for forcing said flange into clamping engagement with the stack of sheets to secure it to the printing frame, said flange forming an abutment wall adapted to be 25 engaged by one end of a printing member, thereby to square said member with the stack of sheets.

3. In a duplicator, a printing frame adapted to receive a stack of sheets to be printed, spaced pins at one end of said frame engageable with one edge of said stack of sheets, thereby to square the stack upon the frame, a substantially 30 U-shaped clamping member having an upright wall the lower edge of which is adapted to engage the adjacent upper surface of the stack of sheets, and threaded elements for forcing the 35 clamping member into clamping engagement with said stack of sheets to secure it to the printing frame, the upright wall of said clamping member forming an abutment adapted to be engaged by one end of a printing member, thereby to 40 square said member with the stack of sheets supported on the frame.

4. In a duplicator, a printing frame upon which the sheets to be printed may be stacked, one upon another, means for securing a plurality of sheets in position on said frame, a rocker having a convex surface, a printing blanket overlying said convex surface and suitably secured thereto, and said securing means having an upright wall for

squaring the rocker with the stack of sheets each time an impression is made on one of said sheets, said sheet securing means permitting all of the sheets of the stack to be printed before the printed sheets are removed from the frame.

5

5. In a duplicator, a printing frame for supporting the sheets to be printed, a rocker having a printing blanket detachably secured thereto and adapted to receive an impression to be transferred onto said sheets, a plurality of transversely disposed slots at one end of the rocker, and a substantially S-shaped hook element secured to one end of said blanket adapted to be selectively received in said slots, thereby to tension the blanket on the rocker.

10

6. In a duplicator, a printing frame for supporting sheets to be printed, a rocker, a printing blanket detachably secured to said rocker and adapted to receive an impression to be transferred onto said sheets, a plurality of transversely disposed slots in an upper wall of the rocker, spaced apart lengthwise of and S-shaped hook elements secured to the blanket and adapted to be received in said slots, thereby to detachably secure the blanket to the rocker.

15

7. In a duplicator, a printing frame for supporting sheets to be printed, a rocker, a printing blanket detachably secured to said rocker and adapted to receive an impression to be transferred onto said sheets, an inwardly turned flange at 20 each end of the rocker, a plurality of transversely disposed slots in said flanges, and S-shaped hook elements secured to each end of said blanket and adapted to be received in said slots and providing means whereby the blanket may be properly tensioned on the rocker.

25

8. In a duplicator, a printing frame having means at one end for squaring the sheets to be printed, a transversely disposed clamping member of channel cross-section having one leg 40 adapted to engage the uppermost sheet of the stack of sheets, thereby to secure the stack in position upon the frame, said clamping member having an upright wall disposed transversely of the sheets, a printing member having a curved 45 surface adapted to be rolled over the uppermost sheet of the stack to make a printing impression thereon, said printing member having one end adapted to be engaged with the upright wall of the clamping member, whereby the printing member is squared with the sheets, and the clamping member being so constructed and related to the printing frame that as each sheet is printed, it may be folded over the clamping member without detaching it therefrom, whereby all of the 50 sheets in the stack may be printed before any of said sheets are removed from the frame.

55

KENNETH O. CHRISTIANSON.
